DESIGN FOR A TROPHY BASE

Dewayne Kenneth Williams, Anaheim, Calif.

Application May 22, 1947, Serial No. 139,211

Term of patent 3½ years

(Cl. D29—23)

To all whom it may concern:

Be it known that I, Dewayne Kenneth Williams, a citizen of the United States, residing at Anaheim, in the county of Orange and State of California, have invented a new, original, and ornamental Design for Trophy Base, of which the following is a specification, reference being had to the accompanying drawing, forming part thereof.

Figure 1 is a view in front elevation of the trophy base embodying my new design; Fig. 2 is a top plan view of the same; Fig. 3 is a view in side elevation of the same; and Fig. 4 is a rear view in elevation of the same.

I claim:

The ornamental design for a trophy base, as shown.

DEWAYNE KENNETH WILLIAMS.
